UNITED STATES PATENT OFFICE.

THOMAS ANDREW, OF ROCHDALE, ENGLAND, ASSIGNOR TO NO. 2 D. R. COTTON MILLS, LIMITED, OF REGENT'S PARK, COUNTY OF LONDON, ENGLAND, A BRITISH COMPANY.

TREATMENT OF CANVAS AND SIMILAR WOVEN FABRICS.

1,425,934.

Specification of Letters Patent. Patented Aug. 15, 1922.

Application filed December 27, 1921. Serial No. 525,186.

To all whom it may concern:

Be it known that I, THOMAS ANDREW, a subject of the King of Great Britain, residing at Royle Cottage, Gipsy Lane, Rochdale, in the county of Lancaster, England, have invented certain new and useful Improvements in or Relating to the Treatment of Canvas and Similar Woven Fabrics, of which the following is a specification.

10 This invention relates to the treatment of canvas and similar woven fabrics, the chief object being to enable the side selvedge produced during the weaving of such fabrics to be broken or destroyed without cutting 15 away the entire selvedge portions, which latter operation results in a waste of material as well as diminishes the width of the canvas or similar fabric. This destruction of the selvedge is desirable in the case of canvas 20 intended for the manufacture of pneumatic tyres and the like.

According to the invention the selvedges of the woven canvas or similar fabric are broken or destroyed by removing certain of 25 the warp threads and simultaneously combing out the ends of weft threads associated with said warp threads. For this purpose the canvas or similar fabric as it is received from the loom may be delivered from a 30 roller to stentering means and passed over a table provided at or near one end thereof with appropriate devices adapted to engage the selvedges of the fabric to effect the removal of the warp threads desired to be 35 removed and also to comb out the ends of the weft threads. Said devices may consist of a cutter in the form of rollers or discs provided with teeth or their equivalent capable of removing say one or two warp threads 40 on either side of the canvas and simultaneously combing out the exposed ends of the weft threads. The said cutter may be driven in any appropriate manner and the canvas after undergoing treatment may be 45 rewound onto a roller situated at the opposite end of the table to the roller from which the canvas is delivered.

In order that the said invention may be clearly understood and readily carried into effect, the same will now be described more fully with reference to the accompanying drawings, in which:

Figure 1 is a sectional elevation,

Figure 2 is a plan, and Figure 3 an end view of the aforesaid device;

Figure 4 is a side elevation showing a contrivance for automatically controlling the position of the device relatively to the selvedges.

Figures 5 and 6 illustrate details hereinafter referred to.

A is the cutter which comprises two rollers or discs having a number of saw-like teeth *a a* at their periphery. Any other number of discs may be employed as may be found necessary for doing the work required of them; and in addition to a saw-toothed disc or discs, one or more discs may be mounted on the same spindle or shaft 70 and furnished with suitably modified peripheral teeth or surfaces for the special function of combing or brushing out the loose fibres, in cases where the action of the rotary saw teeth alone is not found to give 75 a satisfactory result. This cutter A is rotatably mounted in a guard B and is driven by an electric motor C. The cutter and motor are carried by a saddle piece D which is capable of sliding along the guides *d d* 80 transversely with respect to the canvas passing through the machine. The saddle piece is provided with a screw-threaded lug *d'* with which engages a corresponding screw-threaded spindle E rotatably mounted beneath the said saddle piece. The spindle E is adapted to be rotated intermittently for the purpose hereinafter described by means of an electric motor F which is connected through suitable reducing gear *e e* to the 90 said spindle. In the example shown this gear consists of a worm and worm wheel. The said guides *d d* are mounted on a second saddle piece F² which is also capable of sliding transversely along guides *f f* in 95 the frame of the machine that is to say in the same direction that the saddle piece D can slide. This saddle-piece F² is also provided with a screw-threaded lug *f'* which engages the screw-threaded spindle G rotatably mounted in the bed or frame of the table beneath the saddle-piece F² and provided with a hand wheel *g* whereby it can be manually rotated to effect the movement of the saddle-piece F². H is a pin roller 100 rotatably mounted in a steel die which is

105

adjustably fixed on the saddle-piece D in front of the cutter A for holding the canvas in position during the breaking down or destruction of the selvedges.

5 The action of the device is as follows: The canvas (represented by dot-and-dash lines in the drawings) is led over the scrimp rail W and the table of the machine and is connected to the batching up spool K and 10 and is caused to travel over said table by rotating the said spool. The cutter having been set in motion is moved up to the edge of the canvas by rotating the handwheel g in the proper direction. The extent of this 15 movement is such that the teeth of the cutter penetrates the selvedge of the canvas to a distance of say one or two warp threads. As the canvas travels over the table some of the teeth on the cutter act to cut the warp 20 threads while others act to comb out the ends of the waft threads associated therewith. If it is desired to operate upon both selvedges of the canvas simultaneously another cutter arranged and adapted to operate as aforesaid would be mounted upon the 25 opposite side of the table and in this case the spindle G would be prolonged and formed with screw threads of the opposite twist to those shown in Figure 2; that is to say the 30 threads at one end of the spindle would be left handed and at the other end right handed.

In order to compensate for variations in the width of the canvas and at the same time 35 to ensure that the teeth of the cutter penetrate the selvedge of the canvas to the same extent throughout its length an electrically operated device is arranged to control the aforesaid electric motor F and caused it to 40 revolve either in a clockwise or anti-clockwise direction according to the variations which may occur in the width of the canvas and move the saddle piece D, together with the cutter A carried thereby, towards or 45 away from the edge of the canvas so that the said cutter will be automatically displaced in relation to the position to which it was initially adjusted by the hand wheel g. For this purpose we have indicated a rod or 50 feeler L (see Figure 4) which is arranged in front of the cutter A and is fixed to one end of a shaft l which is free to oscillate in bearings M M. At the other end of the shaft l is fixed a contact maker N in circuit 55 with the motor F which is adapted to make contact with the member O. This member comprises two insulated conductors o o' (see Figure 5) separated from one another by means of an insulating strip of material o² and in circuit with the motor F. The feeler 60 L may be kept in contact with the edge of the canvas by suitable means such as a spring so that it always tends to bear lightly upon the edge of the canvas. If during 65 the passage of the canvas past the cutter A

a portion of greater width is met by the feeler L the latter will be angularly displaced and rotate the shaft l thus causing the contact maker N to make contact with one of the conductors o o' and complete the circuit with the motor F in such manner that the latter will move the saddle piece away from the edge of the canvas to compensate for the increased width in the canvas. If a portion of the canvas is met of 70 narrower width the contact maker will be displaced to make contact with the other conductor and so cause the motor to rotate in the opposite direction and move the saddle piece and the cutter towards the edge of 75 the canvas. So long as the width of the canvas remains constant the contact maker rests upon the insulating material o² between the two conductors and thereby renders the motor inoperative. A suitable arrangement of the electrical connections for effecting this control is shown in the diagram, Figure 6, in which P and p indicate high voltage supply conductors, Q a low voltage battery, R and r' relay coils placed 80 on the saddle piece D under the motor F, O and O' low voltage terminals of the relay coils T¹, T², T³ and T⁴ relay high voltage switch terminals and S s' and s² reversing motor terminals. When the contact maker 85 N is moved by the feeler L (Figure 4) to make contact on the terminal O the relay coil R is energised by the battery Q and the switch terminals T¹ and T² are thereby closed so that the high voltage conductor P is connected to the motor terminal S, causing the 90 motor to run in one direction of rotation. When the contact maker N is moved by the feeler L to make contact with the terminal O', the relay coil r' is energized by the battery Q, the switch terminals T³ and T⁴ are 95 closed, and the high voltage conductor P is connected to the motor terminal S', causing the motor to run in the opposite direction. 100

What I claim and desire to secure by Letters Patent of the United States is:—

1. In a machine of the class described, the combination of a support, a saddle transversely mounted on said support, a rotatable cutter secured to said saddle, means on said support for intermittently moving said saddle, said machine adapted to receive a fabric therethrough, and separate means adapted to bring said cutter into contact with the edges of the fabric so as to remove certain of the warp threads therefrom and to simultaneously comb out the ends of the weft threads associated with said warp threads. 115

2. In a machine of the class described, the combination of a support, a saddle transversely mounted on said support, a rotatable cutter secured to said saddle, means on said support for intermittently moving said 120 support 125

saddle, said machine adapted to receive a fabric therethrough, means adapted to bring said cutter into contact with the edges of the fabric so as to remove certain of the warp threads therefrom and to simultaneously comb out the ends of the weft threads associated with said warp threads, and means whereby intermittent lateral adjustment of the cutter relative to the edges of the fabric is automatically effected to compensate for variations in the width of the fabric.

3. In a machine of the class described, the combination of a support, a saddle transversely mounted on said support, a rotatable cutter secured to said saddle, means on said support for intermittently rotating said cutter, said machine adapted to receive a fabric therethrough, means adapted to bring said cutter into contact with the edges of the fabric so as to remove certain of the warp threads therefrom and to simultaneously comb out the ends of the weft threads associated with said warp threads, means for automatically adjusting the cutter relative to said fabric comprising a shaft loosely mounted on said support having depending arms secured at its opposed ends, one of said arms adapted to contact with the edge of the fabric and the other of said arms arranged to be brought into alternative contact with an electric switch so as to control the lateral movement of the cutter.

4. In a machine for destroying the selvedges of woven fabric comprising a supporting table, transversely disposed guides in said table, a saddle adjustably secured to said guides, a pair of guides mounted on said saddle, a second saddle slidably connected to said last mentioned guides having a cutter mounted thereon, means on said saddle for rotating said cutter, said cutter provided with a plurality of cutting discs adapted to remove certain of the warp threads of the fabric as it is conducted through the machine, and to simultaneously

comb out the ends of the weft threads associated with said warp threads.

5. In a machine of the class described, the combination of a support, a saddle transversely mounted on said support, a rotatable cutter secured to said saddle, means on said support for intermittently moving said saddle, said machine adapted to receive a fabric therethrough, separate means adapted to bring said cutter into contact with the edges of the fabric so as to remove certain of the warp threads therefrom and to simultaneously comb out the ends of the weft threads associated with said warp threads, means for automatically adjusting the cutter relative to said fabric comprising a shaft loosely mounted on said support having depending arms secured at its opposed ends, one of said arms adapted to contact with the edge of the fabric and the other of said arms arranged to be brought into alternative contact with an electric switch so as to control the lateral movement of the cutter, and means secured to said table and contacting with the edges of said fabric for automatically adjusting the cutter relative to the fabric for the purpose specified.

6. In a machine of the class described, the combination of a support, a saddle slidably secured to said support, a cutter having a plurality of cutting discs mounted on said saddle, means on said saddle for rotating said cutter, said machine adapted to receive a fabric therethrough, means adapted to bring said cutter into contact with the edges of the fabric, separate means connected to said saddle for moving the latter laterally of said machine, and means operatively associated with said last mentioned means and engaging the edges of the fabric to impart a reciprocating movement to said saddle so as to automatically position the cutter to compensate for variations in the width of the fabric.

THOMAS ANDREW.
